DESIGN FOR A FORK OR ANALOGOUS ARTICLE

Matthew H. Shulman, New York, N. Y.

Application February 15, 1944, Serial No. 112,597

Term of patent 7 years

(Cl. D54—12)

To all whom it may concern:

Be it known that I, Matthew H. Shulman, a citizen of the United States and resident of New York, in the county of New York and State of New York, have invented a new, original, and ornamental Design for a Fork or Analogous Article, of which the following is a specification, reference being had to the accompanying drawing, forming a part thereof, and of which Fig. 1 is a perspective view of a fork or analogous article

showing my new design; Fig. 2 is a sectional view taken on line 2—2 of Fig. 1; and Fig. 3 is a sectional view taken on line 3—3 of Fig. 1.

The dominant features of the design reside in the portions shown in full lines.

I claim:

The ornamental design for a fork or analogous article, substantially as shown and described.

MATTHEW H. SHULMAN.
